Patented Apr. 17, 1928.

UNITED STATES PATENT OFFICE.

EINAR C. CARLSON, OF TWO HARBORS, MINNESOTA.

CROWBAR ATTACHMENT.

Application filed December 4, 1926. Serial No. 152,645.

The present invention relates to a crow bar attachment and aims to provide a device whereby a crow bar may be efficiently used for digging holes such as are incident to the digging of wells or telephone post holes. The attachment is particularly adapted to the use of the crow bar in breaking up the hard clay or rock whether large or small. At the present time it is very difficult to loosen up the clay and rocks in the bottom of holes being dug for the purpose specified and this implement overcomes this difficult task to a considerable extent.

Another important object of the invention lies in the provision of an attachment of this nature which allows the crow bar to be used as a jack for lifting and prying heavy things.

A still further very important object of the invention lies in the provision of an attachment of this nature which is simple in its construction, adjustable, thoroughly efficient and reliable, compact and convenient, and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawing:

Figure 1 is a perspective view of the attachment embodying the features of my invention,

Fig. 2 is a perspective view of a portion thereof,

Fig. 3 is an elevation of the attachment showing the same in use,

Fig. 4 is an elevation showing the attachment folded out of use.

Referring to the drawing in detail it will be seen that the numeral 5 denotes a plate preferably in the form of a disk having a radially extending notch or slot 6. A crank 7 extends centrally from the disk plate 5 and is fixed thereto by means of ears 8 which are riveted as at 9 to the plate although any other fastening means may be utilized. This bar or shank 7 is provided with a longitudinally extending series of transverse apertures 10. A second shank 11 is provided with longitudinal side flanges 12 which overhang the shank 11 and form a

sleeve in which is slidable the first shank 7. A screw, bolt, or like fastening element 14 is threaded through an opening in the shank 11 and engages in the apertures 10 for holding the shank 7 and 11 adjusted in relation to each other so that the shank formed by these two telescopically associated shanks may be adjusted as to length.

The numeral 15 denotes a clamp section of arcuate formation having its terminals provided with oppositely extending ears 16 and its intermediate portion provided with a lug 17 from which extends a pin 18 that pierces a suitable opening provided in the extremity of the shank 11. A coil spring 19 is disposed about the pin 18 between the shank 11 and a washer 20 on the end of the pin 18 held in place by a cotter pin 21. An arcuate clamp section 22 is also provided with ears 23 which are adjustable with ears 16 by means of screws, bolts, or like fastening elements 24. A crow bar 26 is adapted to be received in the clamp and this clamp may be engaged with the crow bar at any point thereof which may be convenient but is preferably engaged adjacent the working point thereof. The plate may be placed up against the bank as shown in Fig. 3 in order that the bottom of a well or hole may be worked so that the clay, rock, and the like may be more easily loosened. It will be obvious that the crow bar may be used as a prying instrument for raising devices such as a jack and in other useful ways by means of this attachment. The shank of the device may be adjusted as may be found necessary from time to time. When the attachment is not in use, it may be folded to the out-of-the-way position shown in Fig. 4 at which time the crow bar will extend through the radial notch or slot 6. The spring 19 will hold the attachment in this position as this spring gives the necessary friction between the lug 17 and the shank 11.

It is thought that the construction, operation, and utility of this invention will now be clearly understood by those skilled in this art without a more detailed description thereof. The preferred embodiment of the invention has been disclosed in detail merely by way of example since in actual practice it attains the features of advantage enumerated as desirable in the statement of the invention and the above description. It will be apparent that changes in the details of

construction, and in the combination and arrangement of parts may be resorted to without departing from the spirit and scope of the invention as hereinafter claimed, or sacrificing any of its advantages.

Having thus described my invention what I claim as new is:

An attachment of the class described including a plate provided with a radial notch, 10 a shank fixed to the plate and extending

perpendicularly therefrom, a second shank slideable on the first shank, means for holding the shanks at different adjustable positions in relation to each other, a clamp, means for pivoting the clamp on the second shank, and spring means holding the clamp and the second shank in frictional engagement.

In testimony whereof I affix my signature.
EINAR C. CARLSON.
